Patented Oct. 14, 1969

215,600

FAUCET ASSEMBLY

Curtis M. Brubaker, Los Angeles, Calif., assignor to
Adams Rite Manufacturing Company, Glendale, Calif.

Filed Oct. 14, 1968, Ser. No. 13,964

Term of patent 14 years

Int. Cl. D23—01

U.S. Cl. D23—25

FIG. 1.

FIG. 2.

FIG. 3.

FIG. 6.

FIG. 5.

FIG. 4.

FIG. 1 is a perspective view of a faucet assembly showing my new design;

FIG. 2 is a top view of the same;

FIG. 3 is an elevational view taken from one side thereof;

FIG. 4 is a front elevational view thereof;

FIG. 5 is a rear elevational view thereof; and

FIG. 6 is a fragmentary perspective view of a modified form of the faucet assembly shown in FIG. 1.

Fragmentary broken line showing of a sink in FIG. 1 is for purposes of illustration only.

I claim:

The ornamental design for a faucet assembly, substantially as shown and described.
